CLAIM

The ornamental design for a packaging clip, as shown and described.

DESCRIPTION

FIG. 1 is a perspective view of a packaging clip showing our new design;

FIG. 2 is a top view thereof, the bottom being the same;

FIG. 3 is a side elevation view thereof, the other side

being the same; and,

FIG. 4 is an end view thereof, the other end being the

same.

FIG-2

FIG-3

FIG-4
